UNITED STATES PATENT OFFICE.

OTTO E. STANDHARDT, OF ATLANTA, GEORGIA, ASSIGNOR OF ONE-HALF TO WILLIAM RITTER, OF ATLANTA, GEORGIA.

GRIP FOR BOWS OF MUSICAL INSTRUMENTS.

Application filed April 30, 1923. Serial No. 635,631.

This invention relates to controllers for bows of musical instruments, and more particularly to adjustable controllers for violin bows or the like.

5 The bows of musical instruments, such as violin bows, consist of a wooden staff having a number of horsehairs or other hair, stretched taut and parallel to the staff. The ends of the horse-hairs are received in a 10 frog which is adjustable on the staff to permit adjustment of the hairs due to changes in climatic conditions and other causes.

In holding a bow, it is customary to place the thumb against the frog. As the frog is 15 moved to loosen or tighten the hair, the position of the thumb is altered and the playing length and leverage of the bow is thus changed each time the frog is moved.

An object of the invention is the provision 20 of a fixed controller on the bow staff which will remain in a fixed position regardless of the adjustment of the frog.

A further object is the provision of a controller having an oval opening for the 25 reception of the thumb, which opening conforms to and suggests the proper oval movement or correct stroke in bowing.

A further object of the invention is to provide a device that may be positioned on 30 the staff to permit and maintain a fixed leverage throughout the entire length of the bow in playing instruments of the violin family.

A further object of the invention is to 35 provide a single device which will fit any size hand without adjustment.

In the form of the invention shown, I provide a split sleeve adapted to surround the staff and having an oval cut-out portion 40 for the reception of the thumb of the user and a raised portion surrounding said cut-out portion.

In the accompanying drawings, I have 45 shown one embodiment of the invention. In this showing:

Figure 1 is a perspective view of a portion of a violin bow showing the invention applied,

Figure 2 is a side elevation of the grip 50 removed,

Figure 3 is a central longitudinal sectional view,

Figure 4 is a transverse sectional view on line 4—4 of Figure 2, and,

Figure 5 is a similar view on line 5—5 of 55 Figure 2.

Referring to the drawings, the reference numeral 1 designates a violin bow staff having a frog 2 arranged adjacent its end. A plurality of strands of hair 3 are secured 60 to the frog. As these parts are of the usual construction, a more detail description thereof is deemed unnecessary. The frog is adjustable longitudinally on the staff in the usual manner, to loosen or tighten the hairs 65 of the bow.

The controller forming the subject matter of the present invention consists of a split sleeve 4 formed of metal or other suitable material and having a substantially oval-shaped cut-out portion 5. Surrounding the cut-out portion, there is provided an extra thickness of material, as indicated at 6. Opposite the cut-out portion, the surface of the grip is roughened, as at 7, and the two 75 ends of the grip are provided with raised edges 8.

The use of the device will be apparent from the foregoing description. The sleeve is sprung over the staff and arranged at a 80 desired distance from the frog. It may be adjusted longitudinally of the staff when the frog is adjusted to tighten or loosen the hairs, and may thus be maintained at a uniform distance from the frog at all times, 85 permitting the user of the bow to properly balance it. The user of the bow places his thumb in the oval cutout portion 5 and the surrounding thickness 6 prevents the thumb from becoming accidentally displaced. The 90 fingers engage the roughened portion 7, which permits the user to maintain a firm grasp on the bow at all times.

By means of the construction shown, having an oval thumb opening and a corrugated 95 surface opposite the thumb opening, it is possible to obtain a secure grip and firm pressure between the end of the thumb and the first joint of the second finger. The size of the grip requires the joint of the second 100 finger to be placed opposite the thumb, whereby the correct rotary motion of the wrist is obtained.

It is to be understood that the form of my invention herewith shown and described 105 is to be taken as a preferred example of the same, and that various changes in the shape, size, and arrangement of parts may be re-

sorted to without departing from the spirit of the invention or the scope of the subjoined claims.

Having thus described my invention, I claim:

1. A controller for bows of musical instruments comprising a split sleeve of substantially uniform thickness having a substantially oval-shaped cut-out portion for the reception of the thumb of the user.

2. A controller for bows of musical instruments comprising a split sleeve of substantially uniform thickness having a substantially oval-shaped cut-out portion for the re-

ception of the thumb of the user, and being provided with an additional thickness of material surrounding said cut-out portion.

3. A controller for bows of musical instruments comprising a split sleeve of substantially uniform thickness having a substantially oval-shaped cut-out portion for the reception of the thumb of the user, and being provided with an additional thickness of material surrounding said cut-out portion, the surface of said sleeve being roughened opposite said cut-out portion.

In testimony whereof, I affix my signature.

OTTO E. STANDHARDT.
